SHIPPING CONTAINER FOR PRODUCE

Roger L. White and Richard C. Miller, Lawrence, Kans., and Lewis E. Young, Salt Lake City, Utah, assignors to The Lawrence Paper Company, Lawrence, Kans., a corporation of Kansas

Application July 18, 1955, Serial No. 522,562

3 Claims. (Cl. 229—37)

This invention relates to shipping containers for produce such as fruits, vegetables and the like, and more particularly, to a folded shipping container of suitable paper board.

In the shipping of perishable produce such as fruits and vegetables, it is desirable that the containers be shaped whereby when stacked during storage and shipping there may be ventilation or air circulation around the containers and produce contained therein, and that the containers provide maximum protection of the contents to prevent or reduce possibility of injury due to loads and impacts occurring during shipping and rough handling.

The objects of the present invention are to provide a novel shipping container structure of suitable paper board such as double-faced corrugated board with side walls having vertical portions and downwardly tapered portions for forming ventilation channels and lateral load-bearing surfaces when a plurality of such containers are arranged in side by side or adjoining relation; to provide such a container with facet wall panels at the corners having angularly arranged upper and lower portions which co-operate with the vertical and tapering portions of the side walls to retain same in position and add rigidity thereto; to provide such a container with a liner having a shape substantially conforming to and engaging the interior of the side walls with registering openings in the liner and side walls for ventilation of the contents of the container, and to provide a shipping container of corrugated board that is shaped whereby it is cut and scored and adapted to be shipped flat and assembled at the point of use in a double wall container having a tapering formation with load-bearing substantially vertical surfaces in each side wall; and to provide such a container that is economical to manufacture, and easily assembled in a shipping container of improved impact and stacking strength and that permits ventilation during storage and shipping to give protection to fruit and produce contained therein.

In accomplishing these and other objects of the invention, we have provided improved details of structure, the preferred forms of which are illustrated in the accompanying drawings, wherein:

Fig. 1 is a top perspective view of a shipping container embodying the features of the present invention.

Fig. 2 is a vertical sectional view through the shipping container taken on the line 2—2, Fig. 3.

Fig. 3 is a horizontal sectional view through the shipping container on the line 3—3, Fig. 2.

Fig. 4 is a plan view of the outer wall portion of the shipping container.

Fig. 5 is a top perspective view of a modified form of shipping container.

Fig. 6 is a partial top perspective view of the modified form of shipping container with the top flaps in open position to illustrate the liner therein.

Referring more in detail to the drawings:

1 designates a shipping container generally consisting

2

of, an outer member or box 2 with a bottom closure 3 and a top closure 4, an inner bottom 5 and a wall liner 6, all fabricated from suitable paper board such as double-faced corrugated board that is of high strength, moisture-resistant and relatively stiff when wet. The outer member 2 of the shipping container is preferably formed from a cut and scored blank 7 illustrated in Fig. 4, and including a main body portion 8 of generally segmental shape or form. On one of the side edges of the blank 7

5 are extensions 9, 10, 11 and 12 forming bottom closing flaps of the shipping container, and upon the opposite side the blank is provided with extensions 13, 14, 15 and 16 preferably forming top closing flaps. The extensions 9, 10, 11 and 12 have their inner edges defined respectively by score lines 17, 18, 19 and 20 arranged in end to end angular relation and extending generally longitudinally of the blank. The extensions 13, 14, 15 and 16 have their inner edges defined respectively by score lines 21, 22, 23, and 24, arranged in end to end angular relation whereby the score lines 21, 22, 23 and 24 are substantially parallel to the score lines 17, 18, 19 and 20 respectively. The extensions 9 and 10 are separated by a line of cut 25; the extensions 10 and 11 are separated by a line of cut 26; and the extensions 11 and 12 are separated by a line of cut 27. The extensions 13, 14, 15 and 16 are separated by cuts 28 whereby the end edges 29 and 30 of each of said extensions are substantially perpendicular to the respective score lines 21, 22, 23 and 24.

30 Extending longitudinally of the blank and arranged in end to end angular relation are a plurality of straight score lines 31, 32, 33 and 34 arranged intermediate the side edges of the main body portion and parallel with the score lines 21, 22, 23 and 24 respectively. Diverging score lines 35 and 36 extend from the intersection of the score line 17 and end edge 37 of the extension 9 to the score line 31 and score line 38 in an end flap 39 on the body member 8, and then the score lines 35 and 36 converge to a point of intersection of the score line 21 and end edge 29 of the extension 13. Corresponding diverging score lines 40 and 41 extend from the line of cut 25 to the score lines 31 and 32 and then converge to the intersection of the cup 28 that separates the extensions 13 and 14 and the intersection thereof with the ends of the score lines 21 and 22. Corresponding scores lines 42 and 43 extend from the ends of the line of cut 26 to the score lines 32 and 33, and then converge to the adjacent ends of the score lines 22 and 23 where they intersect the line of cut 28 between the extensions 14 and 15. Corresponding score lines 44 and 45 diverge from the end of the line of cut 27 to the score lines 33 and 34, and then converge to the adjacent ends of the score lines 23 and 24 where they intersect the line of cut 28 between the extensions 15 and 16.

55 The end of the body member opposite from the flap 39 is preferably cut on a line 46 whereby the body portion defined by the score lines 20, 45, 24, and end edge 46, is a side wall 47 and substantially the same shape as the body portion or side wall 48 defined by the score lines 18, 41, 22 and 42, and the body portion or side wall 49 defined by the score lines 17, 36, 21 and 40 corresponds to the body portion or side wall 50 defined by the score lines 19, 43, 23 and 44.

In the illustrated structure, hand holds 51 and 52 are 65 cut in opposed body portions, for example, between the score lines 17 and 31 and 19 and 33 respectively. Also, the body portion is provided with a plurality of spaced apertures 53 forming ventilating openings as later described.

70 In setting up the outer member or box 2 of the shipping container, the blank 7 is bent on the score lines 35, 36, 40, 41, 42, 43, 44 and 45 whereby the end portion of

the flap 39 extends beyond the end edge 46 and overlies the adjacent body portion and is secured thereto by suitable fastening devices 54. In so bending the body portion, the upper portions 55 of the respective body portions as between the respective score lines 21, 31, 22, 32, 23, 33, and 24, 34, is substantially vertical and the portions 56 below the score lines 31, 32, 33 and 34 taper downwardly and inwardly, and the portions between the respective score lines 35, 36, 40, 41, 42, 43 and 44, 45, form corner facets or panels which are inclined inwardly and downwardly from the upper corners of the container to the intermediate score lines and then taper inwardly and downwardly at a lesser degree from the intermediate score lines to the bottom corners of the containers. When so arranged, the upper portions 55 of opposed side walls are substantially parallel and the upper ends of said upper wall portions of the side walls collectively form a periphery defining an upper opening 57 for the container and the lower ends of the inwardly tapering wall panels 56 define a lower opening 58 for the container, the periphery of the lower opening being smaller than the periphery of the upper opening and the periphery of the lower opening lying within the area overhung by the periphery of the upper opening.

The extensions 9, 10, 11 and 12 are folded inwardly and upwardly in overlapping relation to provide the bottom closure 3 and said extensions are then suitably secured in closed condition by suitable fastening devices 59 such as staples or gummed tape. The inner bottom 5 is cut from a sheet of corrugated board and conforms to the shape of the interior of the container at the bottom opening thereof whereby said inner bottom may be placed in the outer member of the container and moved into overlying relation to the bottom closure 3.

A liner 6 is cut and scored in substantially the same manner and relationship as the body portion 8 of the outer member whereby the liner may be arranged in tubular form with the walls thereof closely engaged with the inner surfaces of the walls of the outer member, and substantially conform to the shape thereof. When the container is filled, the extensions 13, 14, 15 and 16 are folded inwardly and downwardly into overlapping relation and suitably secured in closed condition by suitable fastening devices, for example, a strip of gummed tape 60.

When a plurality of filled containers are placed in stacked condition and side by side relation, the vertical or upper portions 55 of the side walls provide bearing surfaces between adjoining containers when stacked together, and the inwardly tapered portion provide horizontal channels for air flow, and the facet corners provide vertical channels whereby air can circulate around the sides of the container and also enter the apertures 53 in the outer member and pass through the registering apertures 61 in the liner for movement around the contents of the container. The vertical portion of the side walls of the container are of suitable size to form load bearing surfaces that are ample to take and absorb the impact imparted to stacked containers as for example in freight cars during rough handling, switching and the like, whereby the impact loads are absorbed by the container and are not transmitted to the contents in sufficient force to injure the contents of the container.

In the form of the invention illustrated in Figs. 5 and 6, the lower portion of the container is substantially identical with the form illustrated in Figs. 1 to 4 inclusive. The upper portion of the container differs only in that the converging portion of the score lines 35, 36, 40, 41, 42, 43, 44 and 45 intersect with the score lines 21, 22, 23 and 24 in laterally spaced relation whereby the upper configuration of the container is provided with what may be termed "beveled corners" 62 as illustrated in Fig. 5 instead of the square configuration illustrated in Fig. 1. The upper extensions also are cut at an angle as at 62 adjacent the score lines defining hinge connections there-

of with the body portion whereby when the extensions are folded in overlapped condition for closing the container, the extensions define the same periphery as the body of the container.

From the foregoing, it will be readily apparent that we have devised a new and novel shipping container of unique shape that when a plurality are arranged in adjoining and stacked condition, ventilating passages will be formed therebetween and there will be contacting lateral load-bearing portions which substantially reduce possibility of injury to the contents of the container during shipment.

What we claim and desire to secure by Letters Patent is:

1. A shipping container for fruit and garden produce formed of foldable paper board, said container having a plurality of connected side walls wherein opposed side walls have parallel upper portions disposed in parallel planes and inwardly and downwardly inclined lower portions, a score line defining the juncture of the upper and lower portions of each side wall, the upper ends of the upper portions of the side walls collectively defining the upper opening of the container, and the lower ends of the lower portions of the side walls collectively defining the bottom opening of the container, the upper and bottom openings each being of rectangular cross section with the area of the upper opening being greater than the area of the bottom opening, corner panels connecting the adjacent side walls throughout their height, said corner panels each being defined by pairs of score lines diverging from the lower ends of the side walls to the score lines defining the juncture of the upper and lower portions of the adjacent side walls and then converging to the upper ends of the side walls, closure flaps hingedly connected to the lower ends of the side walls for closing the bottom opening of the container, and closure flaps hingedly connected to the upper ends of the side walls for closing the upper opening of the container, said side walls having a plurality of mutually spaced apertures therein, said upper parallel portions of the container being of suitable height whereby said container is characterized by the parallel portions of the side walls providing bearing surfaces between adjoining containers and the inclined lower portions and corner panels providing horizontal and vertical air passages between adjoining containers when stacked together.

2. A shipping container for fruit and garden produce formed of stiff, high strength, moisture-resistant double-faced corrugated paper board, said container having a plurality of connected side walls wherein opposed side walls have parallel upper portions disposed in parallel planes and inwardly and downwardly inclined lower portions, a score line defining the juncture of the upper and lower portions of each side wall, the upper ends of the upper portions of the side walls collectively defining the upper opening of the container, and the lower ends of the lower portions of the side walls collectively defining the bottom opening of the container, the periphery of the upper opening being substantially greater in length than the periphery of the lower opening, corner panels connecting the adjacent side walls, said corner panels each being defined by pairs of score lines diverging from the lower ends of the side walls to the score lines defining the juncture of the upper and lower portions of the adjacent side walls and then converging to the upper ends of said side walls, score lines extending across the corner panels at the greatest width thereof and defining upper and lower portions of the corner panels which are angularly related to form downwardly and inwardly inclined portions with the upper portion being inclined inwardly at a greater degree than the lower portion, said score lines defining the juncture of the upper and lower portions of the side walls and the score lines extending across the corner panels all being in a plane parallel to the lower ends of the side walls, closure flaps hingedly connected to the lower ends of the side walls for closing

the bottom opening of the container, and closure flaps hingedly connected to the upper ends of the side walls for closing the upper opening of the container, said side walls having a plurality of mutually spaced apertures therein, said upper parallel portions of said container being of suitable height whereby said container is characterized by the parallel portions of the side walls providing bearing surfaces between adjoining containers and the inclined lower portions and corner panels providing horizontal and vertical air passages between adjoining containers when stacked together.

3. A shipping container for fruit and garden produce and formed of stiff, high strength, moisture-resistant double-faced corrugated paper board, said container having a plurality of connected side walls wherein opposed side walls have upper portions disposed in parallel planes and inwardly and downwardly inclined lower portions, a score line defining the juncture of the upper and lower portions of each side walls, the upper ends of the upper portions of the side walls collectively defining the upper opening of the container, and the lower ends of the lower portion of the side walls collectively defining the bottom opening of the container, said upper and bottom openings being substantially square in cross section, the periphery of the upper opening being substantially greater in length than the periphery of the bottom opening, corner panels connecting the adjacent side walls, said corner panels each being defined by pairs of score lines diverging from the lower ends of the side walls to the score lines defining the juncture of the upper and lower portions of the adjacent side walls and then converging to the upper ends of the side walls, score lines extending across the corner panels at the greatest width thereof and defining upper and lower portions of the corner panels which are angularly related to form downwardly and inwardly in-

25

clined portions with the upper portion being inclined inwardly at a greater degree than the lower portion, said score lines defining the juncture of the upper and lower portions of the side walls and the score lines extending across the corner panels all being in a plane parallel to the plane of the upper ends of said upper portions of the side walls, a liner in the container and having side walls and corner panels substantially corresponding in shape and coextensive with the side walls and corner panels of the container and snugly engaging the interior thereof, said side walls and liner having a plurality of mutually spaced registering apertures therein, closure flaps hingedly connected to the upper ends of the side walls for closing the upper opening of the container, and closure flaps hingedly connected to the lower ends of the side walls for closing the bottom opening of the container, said upper parallel portions of said container being of suitable height whereby said container is characterized by the parallel portions of the side walls providing bearing surfaces between adjoining containers and the inclined lower portions and corner panels providing horizontal and vertical air passages between adjoining containers when stacked together.
